(57) **CLAIM**

The ornamental design for a pendant hanger, as shown and described.

DESCRIPTION

FIG. 1 is an environmental front perspective view of a pendant hanger embodying my design.

FIG. 2 is a front perspective view thereof.

FIG. 3 is a rear perspective view thereof.

FIG. 4 is a front view thereof.

FIG. 5 is a rear view thereof.

FIG. 6 is a top plan view thereof.

FIG. 7 is a bottom plan view thereof.

FIG. 8 is a right side elevational view thereof; and,

FIG. 9 is a left side elevational view thereof.

The broken line throughout the drawings forms no part of the claimed design.
